COMBINED LIPSTICK AND PERFUME CONTAINER

William O. Mitchell, Baltimore, Md.

Application May 23, 1938, Serial No. 209,401

1 Claim. (Cl. 132—79)

This invention relates to a combined lipstick and perfume holder, and has for its object to provide a device in which a lipstick is carried and which can be removed at any time when it is desired to use the same; also, to provide a chamber in which liquid perfume can be carried and which is provided with a cap for sealing the liquid chamber, said cap being provided with an applicator which projects into the perfume chamber, and which is used for applying the perfume to the person or wearing apparel whenever desired. A further object of the invention is to provide a compact lipstick and perfume holder which can be carried in the purse in the same manner as the lipsticks now in general use.

The invention consists of the novel construction and arrangement of the parts and combination of parts hereinafter more fully set forth in the following specification and pointed out in detail in the appended claim.

In the accompanying drawing:

Figure 1 is an elevation of my invention.

Figure 2 is a vertical longitudinal section of Figure 1.

Figure 3 is a detail view of the lipstick holder.

Figure 4 is an inverted plan view of Figure 2.

Figure 5 is a side elevation of a modification of my invention.

Figure 6 is a vertical longitudinal section of Figure 5.

Referring to the accompanying drawing, forming part of this specification, and in which like reference numerals designate like parts throughout the several views thereof, 1 designates a casting which, in the present instance, is cylindrical but may be square or any other desired shape, and has a partition 2 near the center thereof to form the chambers 3 and 4. The lipstick holder 5 is of the usual construction in which the lipstick 6 can

be moved up and down by turning the disk 7 on the lower end thereof. The said lipstick holder

5 fits within the chamber 4 and is held therein by the tang 8 projecting from the side thereof and can be removed whenever it is desired to use the lipstick. The chamber 3 is provided with a cap 9, screw-threaded on the end of the cylinder 5 and has a gasket 10 which rests on the top of the chamber 3 and forms a liquid-tight joint. Projecting inwardly from the cap 9 is an applicator 11 in the end of which is carried a piece of absorbent material 12. The applicator 11 and the absorbent material 12 project down into the liquid perfume which is carried in the chamber 3 and when it is desired to apply the perfume to the person or article of clothing, the cap 9 is removed and the perfume applied by touching the person or clothing with the absorbent end of the applicator.

In Figures 5 and 6, I have shown a modification of my invention in which the two chambers 13 and 14 are formed of one piece of metal with the chamber 13 for the lipstick holder projecting into the perfume chamber 14, the lipstick holder and applicator being the same as shown in the other figures.

Having thus described my invention, what I claim is:

A container comprising a metal cylinder screw-threaded on one end on its outer surface and having a central partition therein forming two chambers in said container, a cap having an annular screw-threaded flange and adapted to be screwed on the threaded end of said container to close one of said chambers, a gasket within said cap and adapted to rest on the screw-threaded end of said container to close one of said chambers, a hollow applicator secured to the inner surface of said cap and projecting into one of said chambers, and a wick fitted into, and projecting beyond, the inner end of said applicator.

WILLIAM O. MITCHELL.
